UNITED STATES PATENT OFFICE

MICHAEL B. MENNIGES, OF ST. LOUIS, MISSOURI

SPEED CONTROLLING MEANS FOR ENGINES

Application filed January 12, 1927. Serial No. 160,559.

My invention relates to a central control designed to be utilized in the operation of cane mills, and has for its object to employ a relatively simple device which makes it possible for one man, conveniently positioned, to control the operation of the entire cane mill tandem. This operator can readily and quickly increase or diminish the speed of the cane carrier, or entirely stop the same, as well as increase or diminish the speed of the various crushers and mills in the tandem, or entirely stop the same, as may be desired or necessary in order to grind the maximum capacities and overcome the possibility of choking one of the mills of the series in the tandem.

Another feature of my device is that it permits the operator to note the passage of any bulky foreign material through the cane mills and to quickly shut down the operation of the mills in order that said foreign object may be removed before serious damage is done to the milling equipment. While the operator does not see the foreign material itself, he can determine its presence by the rising of the weights on the hydraulic accumulators. After the foreign material has been removed from the mill tandem the mills may again be started into operation by the operator.

In order to make it possible to control the speed of the Corliss engines which drive the mill tandem I have provided a simple device which makes it possible for the operator, conveniently positioned, to control the speed of the engine by hand independently of the regular flyball governor which automatically controls the speed of the engine when running normally.

Fig. I is a diagrammatic cross-sectional view of a mill house.

Fig. II is an enlarged elevation of the governing mechanism for controlling the speed of an engine.

Fig. III is an end view of the governor and hand control mechanism.

Fig. IV is a detail view taken on line IV—IV, Fig. III.

In the drawings, A designates a cane mill tandem driven by a series of gears B by

means of Corliss engines, such as C. D is a raised platform upon which the operator of the cane milling mechanism is positioned. E is a drum control for the Corliss engines C, and F is a control for the cane carrier engines. The control F operates to open or close the valve G which admits steam to the engines for driving the cane carrier.

It will be noted that the lower end 1 of the control rod F is screw-threaded and has upper and lower stops 2 and 3, respectively, positioned thereon. Between these stops a special nut 4 is placed on the screw-threaded lower end 1, to which nut is attached one end of bell crank 5. To the other end of the bell crank 5 a link 6 is pivoted, which in turn is fastened to another bell crank 7. 8 designates a rod also pivoted to the bell crank 7 which controls the opening or closing of the valve G. It will be noted that upon the operation of the handle of the control F by the operator the special nut 4 will be raised or lowered to a predetermined point controlled by the stops 2 and 3, whereby the valve G may be opened or closed to such extent as may be desired. The drum control E is provided with a flexible cable H which, as noted in Fig. I, passes down beneath the platform D over a series of sheaves I to the controlling device for the Corliss engines C.

It will be noted by reference to Figs. II, III and IV that the flexible cable H is connected to a spring 9 so that some elasticity in the operation of said cable may be provided for. To the upper end of the spring 9 a chain 10 is secured which passes over a sheave J and is fastened to a link 11, which link in turn is secured to a double arm 12. The double arm 12 is loosely mounted on the rock shaft 13, that is, it is not keyed thereto.

14 designates a specially constructed single arm which is mounted on and keyed to the rock shaft 13. At the outer end of the arm 14 a perforation is provided through which a threaded rod 15 passes which is pivotally secured at 16 to the end of the double arm 12. 17 is a spring mounted on said rod 15 between a nut 18 threaded upon the outer end of said arm 15 and one side of the free end of the specially constructed single arm 14. The

purpose of this spring 17 is to securely hold the double arm 12 in operative position so that said arm may be at all times under the control of the fly ball governor K.

19 is a weight mounted on a rod 20 which is positioned on the rock shaft 13. 21 is a rod which connects with the fly ball governor K through the pin 22. The purpose of this weight is to determine the speed of the Corliss engines when automatically controlled by the fly ball governor K. 23 is a governor column mounted on the side of the engine frame C. 24 and 25 are governor connecting rods which are pivotally secured at one end to the double arm 12 and control admission of and the cutting off of the steam into the Corliss engine cylinders. As this mechanism and its associated parts about the engine constitute no part of my present invention, I will not refer to it in any greater detail. 26 is a counterbalance weight to assist in pulling the double arm 12 back to normal position.

It will be noted that when the operator turns the drum E to put a pull on the flexible cable H the lower end of the double arm lever 12 is moved, which moves the upper end of said double arm lever in a direction opposite to the movement of the lower end thereof, thereby compressing the spring 17. This movement of the double arm lever moves the governor connecting rods 24 and 25 to diminish the amount of or completely shut off steam to the Corliss engines C. When the operator moves the drum E to permit the flexible cable H to return to its normal position, the double arm lever 12 is moved back to the normal position shown in Fig. II by virtue of the spring 17 and the counterbalance weight 26. It is evident that the amount of movement of the double arm lever 12 may be independently controlled by the operator through the movement of the drum E, so that if he wants to slow up or stop the Corliss engines C he may quickly do so by the amount of movement of the drum E. When the desired speed of the engine has been reached the operator ceases to rotate the drum E. If he desires to stop the Corliss engines completely he rotates the drum E sufficiently to entirely cut off the admission of steam to the engines C. As soon as the drum E is rotated to permit the spring 17 and the counterbalance weight 26 to return the double arm lever 12 to its normal position, the engines will again operate under the automatic control of the fly ball governor K.

I claim:

1. In a device of the character described, an engine having means for regulating the speed thereof, a device for controlling the speed of said engine, said device comprising a double arm loosely mounted upon a shaft, one end of said double arm being connected to a device located on an operator's plat-

form, a single arm keyed to said shaft, a rod connected to one end of said double arm and extended through an opening in said single arm, a spring interposed between the free end of said single arm and the free end of said rod for restoring the double arm to normal position when the pull on said double arm is released, and elements for connecting the ends of said double arm to the speed-regulating means of said engine.

2. In a device of the character described, an engine having means for regulating the speed thereof, means for manually controlling the speed of said engine, said means consisting of a double arm loosely mounted upon a shaft, one end of said double arm being connected to a controlling device positioned on an operator's platform, a rod pivotally connected to the other end of said double arm, a single arm keyed to said shaft, said rod passing through an aperture in the free end of said single arm, a spring mounted upon said rod and adapted to contact with the side of the free end of said single arm, away from the end of said double arm, and adapted to normally hold said double arm out of operative position and to restore said double arm to inoperative position when the device on the operator's platform is released after causing the double arm to move into position to lessen the speed of the engine, and elements for connecting the ends of said double arm to the speed-regulating means of said engine.

In testimony that I claim the foregoing I hereunto affix my signature.

MICHAEL B. MENNIGES.
